UNITED STATES PATENT OFFICE.

HENRY CLAY BASCOM, OF LANSINGBURG, NEW YORK, ASSIGNOR TO S. B. SEXTON & SON, OF BALTIMORE, MARYLAND.

DESIGN FOR A RANGE.

SPECIFICATION forming part of Design No. 21,599, dated May 31, 1892.

Application filed April 28, 1891. Serial No. 390,839. Term of patent 14 years.

To all whom it may concern:

Be it known that I, HENRY CLAY BASCOM, a citizen of the United States, residing in the village of Lansingburg, in the county of Rensselaer and State of New York, have invented and produced a new and original Design for a Range or Stove, of which the following is a specification, reference being had to the accompanying drawing, showing said new design.

The characteristic feature of this design consists of united pairs of right and left foliate scroll branches, as $a a' a^2 a^3$, shaped and

disposed on a side of a range or stove so as to present, essentially, the appearance represented by the accompanying drawing.

What I claim is—

The design for a stove or range, substantially as shown and described.

In testimony whereof I hereunto set my hand, in the presence of two subscribing witnesses, this 25th day of April, 1891.

H. CLAY BASCOM.

Witnesses:

CHARLES H. BENEDICT,
ROBERT GALBRAITH.
